CLAIM

The ornamental design for a trigger for guns as shown and described.

DESCRIPTION

The file of this patent contains at least one drawing/photograph executed in color. Copies of this patent with color drawing(s)/photograph(s) will be provided by the Office upon request and payment of the necessary fee.

1. Trigger for guns

1.1 : Perspective

1.2 : Front

1.3 : Right

1.4 : Left

1.5 : Top

1.6 : Perspective

Reproduction 1.6 is a referential perspective view showing the state in use of the claimed design and forms no part of the claimed design; the circle in red of reproduction 1.6 is only to indicate the claimed design and forms no part thereof.

The broken lines in the drawings disclose unclaimed portions of the trigger for guns only and form no part of the claimed design.
